UNITED STATES PATENT OFFICE

HAROLD C. NOE, OF EAST ORANGE, NEW JERSEY, ASSIGNOR TO WILLIAM R. NOE & SONS, OF BROOKLYN, NEW YORK, A COPARTNERSHIP COMPOSED OF WILLIAM R. NOE, CHARLES E. NOE, AND HAROLD C. NOE

DESIGN FOR A LAMP SHADE

Application filed April 8, 1932. Serial No. 43,427. Term of patent 14 years.

To all whom it may concern:

Be it known that I, HAROLD C. NOE, a citizen of the United States, residing at East Orange, in the county of Essex and State of New Jersey, have invented a new, original, and ornamental Design for Lamp Shades, of which the following is a specification, reference being had to the accompanying drawing, forming part thereof.

I claim:

The ornamental design for a lamp shade substantially as shown and described.

HAROLD C. NOE.
